[57] CLAIM

The ornamental design for an hourglass pendant watch, substantially as shown and described.

DESCRIPTION

FIG. 1 is a front perspective view of an hourglass pendant watch showing my new design on an enlarged scale;

FIG. 2 is a front elevational view thereof with the chain omitted for ease of illustration;

FIG. 3 is a typical side elevational view thereof with the chain omitted for ease of illustration;

FIG. 4 is a rear elevational view thereof with the chain omitted for ease of illustration.
